(57) **CLAIM**

The ornamental design for a connection hub for a surgical tool, as shown and described.

DESCRIPTION

FIG. 1 is a perspective view of a connection hub for a surgical tool in accordance with the new design;

FIG. 2 is a front view of the connection hub for a surgical tool of FIG. 1;

FIG. 3 is a rear view of the connection hub for a surgical tool of FIG. 1;

FIG. 4 is a left side view of the connection hub for a surgical tool of FIG. 1;

FIG. 5 is a right side view of the connection hub for a surgical tool of FIG. 1;

FIG. 6 is a top view of the connection hub for a surgical tool of FIG. 1; and,

FIG. 7 is a bottom view of the connection hub for a surgical tool of FIG. 1.

In the drawings, the broken lines illustrate portions of the connection hub for a surgical tool that form no part of the claimed design.

1 Claim, 4 Drawing Sheets
